UNITED STATES PATENT OFFICE.

JAMES BARKER, OF DETROIT, MICHIGAN.

INDEX DEVICE.

1,384,882.

Specification of Letters Patent. Patented July 19, 1921.

Application filed December 6, 1917. Serial No. 205,733.

To all whom it may concern:

Be it known that I, JAMES BARKER, a citizen of the United States of America, residing at Detroit, in the county of Wayne and State of Michigan, have invented certain new and useful Improvements in Index Devices, of which the following is a specification, reference being had therein to the accompanying drawings.

10 This invention relates to index devices and refers more particularly to improvements in index devices of that character wherein the name-carrying card or the like is sheathed or housed within a celluloid or 15 other transparent casing.

In devices of the character above mentioned the strip-carrying member formed of celluloid has generally been constructed as an open-ended flattened tube, the strip of 20 paper or cardboard being inserted through the end of the strip.

The present invention contemplates an improved transparent strip holder whereby the strip can be more conveniently inserted than 25 in the devices now in use, the holder being preferably so constructed that the paper strip can be inserted in the celluloid strip by a transverse rather than a longitudinal movement. Other objects of the invention 30 are to provide a construction which can be economically manufactured and will be more convenient in use than the present devices of this kind; to provide an improved signaling mechanism in combination with the celluloid 35 strip holder; and in general to provide a new and improved index device of the character set forth.

In the drawings:

Figure 1 is a plan view of an index device 40 embodying my invention;

Fig. 2 is a cross-section on the line 2—2 of Fig. 1;

Fig. 3 is an enlarged front elevation of one of the strips removed;

Fig. 4 is an enlarged cross-section on the line 4—4 of Fig. 1.

Describing in detail the particular construction shown in the drawings, A designates a frame having at its opposite edges 50 return-bent flanges B and C, beneath which the free ends D' and D² of the strips are inserted. The frame is provided at its lower end with a suitable supporting ledge D³ on which the strips rest.

55 In devices of this kind the individual strips comprise a celluloid cover E adapted

to removably receive a strip of paper or cardboard F on which the name and telephone number is written or printed. Whenever it is desired to change one of the strips 60 the particular strip is bent outward so as to contract the distance between its ends to less than that between the flanges B and C. In re-inserting the strip the reverse operation takes place, the strips above the place where 65 it is desired to insert a new one being slid upward.

However, in changing the paper or cardboard strips F in the holders E difficulty is often encountered in getting the strip to fit 70 into the end of the holder. In the present invention this objection is overcome by the novel construction of holder, as shown in detail in Fig. 4. This holder comprises a back portion E' having at its bottom a bend 75 E² and integrally connected with its forward or face portion E³. It will be noticed that this portion terminates at the top about on the line or slightly below the top of the back portion E'; also that it is inwardly 80 bent at E⁴ so as to frictionally hold the paper strip F to prevent it being accidentally disengaged from the holder. To facilitate the insertion and removal of the name strip into the holder, the latter preferably 85 has its corners cut away at G and G' so as to leave the projecting corners of the strip where they can be conveniently taken hold of, particularly in removing the strip.

The transparent holding strip, above described, has a further advantage, in that it permits the use of a signaling device which can be attached or removed without taking the holder out of the frame. These signaling devices H are formed of red, green or 95 other colored celluloid and at their upper ends have a transverse flange H' to facilitate the insertion and removal of the signal, the detailed construction of which is shown in Fig. 4.

100 The signal is relatively short in length with reference to that of the strip and can be slid along into various positions, that is to the left or to the right or to the center of the strip, thus allowing additional signaling to be obtained by the position of the signal with reference to the ends of the strip.

110 While I have shown and described the invention in connection with a particular type of frame it is obvious that the use of the strip and the signaling devices are not confined to any particular type of holding

frame, and that various changes in the details of construction and arrangements and combinations of parts can be made within the scope of my invention.

5. What I claim as my invention is:—
1. The combination with a holding strip formed of celluloid or like transparent material having an opening along one longitudinal edge thereof, of a signal device comprising a colored member insertible through the opening in the longitudinal edge of the holding strip, said signal device having a transverse flange projecting upward from the holding strip.

- 15 2. The combination with an elongated

card holding strip of transparent material folded lengthwise forming adjacent portions between the free longitudinal edges of which a card may be inserted, of a frame providing a mounting for said strip detachably engaged by the extremities of the latter.

3. A card holding strip formed of transparent material and of a substantial U-shape, the sides of said strip being inclined toward each other as they extend from the bend of the strip to frictionally engage a card received in said holder.

In testimony whereof I affix my signature.

JAMES BARKER.
